(57) **CLAIM**

The ornamental design for a smart watch with earphones, as shown and described.

DESCRIPTION

FIG. 1 is a front elevation view of a smart watch with earphones showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a front elevation view of the first accompanying earphone of the smart watch with earphones shown separately to show aspects of the design that are not visible when combined;

FIG. 10 is a back elevation view thereof;

FIG. 11 is a left-side view thereof;

FIG. 12 is a right-side view thereof;

FIG. 13 is a top plan view thereof;

FIG. 14 is a bottom plan view thereof;

FIG. 15 is a perspective view thereof;

FIG. 16 is another perspective view thereof;

FIG. 17 is a front elevation view of the second accompanying earphone of the smart watch with earphones shown separately to show aspects of the design that are not visible when combined;

FIG. 18 is a back elevation view thereof;

FIG. 19 is a left-side view thereof;

FIG. 20 is a right-side view thereof;

FIG. 21 is a top plan view thereof;

FIG. 22 is a bottom plan view thereof;

FIG. 23 is a perspective view thereof;

FIG. 24 is another perspective view thereof;

FIG. 25 is a perspective view of the smart watch with earphones; and,

FIG. 26 is an exploded perspective view of the smart watch with earphones.
